UNITED STATES PATENT OFFICE.

EDWARD J. FRITSCH AND RALPH W. NAZEL, OF PHILADELPHIA, PENNSYLVANIA,
ASSIGNORS TO JOHN NAZEL, OF PHILADELPHIA, PENNSYLVANIA.

FLUID-POWER HAMMER.

1,268,231.

Specification of Letters Patent.

Patented June 4, 1918.

Application filed December 26, 1916. Serial No. 138,769.

To all whom it may concern:

Be it known that we, EDWARD J. FRITSCH and RALPH W. NAZEL, citizens of the United States, and residents of the city of Philadelphia, county of Philadelphia, and State of Pennsylvania, have invented certain Improvements in Fluid-Power Hammers, of which the following is a specification.

10 This invention is an improved mechanism designed primarily for providing greater efficiency in fluid power hammers, but it is adapted for more general use, as wherever it is desired to effect the control of 15 fluid pressure in the manner here applied to the operation of a hammer.

Characteristic advantages of the improvements are their simplicity, capacity for utilizing compressed fluid in both the up and down strokes of the ram whether operated continuously or to strike a single blow and 20 vise the work, convenience of operation by comparatively slight movements of parts to effect the several functions, and capacity 25 for ready application to existing constructions.

In the accompanying drawings, Figure 1 is a part sectional elevation of a hammer embodying our improvements; Fig. 2 is a 30 sectional view taken on the line 2—2 of Fig. 1; Fig. 3 is a sectional view taken on the line 3—3 of Fig. 2; Fig. 4 is a sectional view taken on the line 4—4 of Fig. 2; Fig. 5 is a sectional view taken on the line 5—5 35 of Fig. 4; Fig. 6 is an enlarged sectional view taken on the bent line 6—6 of Fig. 2 illustrating the position of the valve mechanism for the continuous reciprocation of the ram; Fig. 7 is a view of the mechanism 40 illustrated in Fig. 6; in a second position, for vising; Fig. 8 is a view of the same valve mechanism in position for holding the ram suspended; Fig. 9 is a developed view 45 of the cylindrical valve; and Fig. 10 is a developed view of the stationary cylinder or bushing in which the cylindrical valve operates.

The drawings illustrate the invention embodied in an air hammer comprising the 50 frame 1 provided with the cylinders 2 and 3 connected at their tops by the respective passages 4 and 5 with the respective passages 6 and 7 of a valve casing 8 which is separable from the cylinders 2 and 3, and 55 connected therewith by bolts 9. The cylin-

ders 2 and 3 are connected at their bottoms by the respective passages 10 and 11 (similar to 4 and 5) with the respective passages 12 and 13 of the valve casing 8. The cylinders 2 and 3 with the passages 4, 5, 60 10 and 11 are of a type heretofore used, excepting that divisional devices 4^a and 10^a have been placed in the transverse cylindrical openings, formerly used as valve 65 seats, to provide the separated passages 4 and 5, and 10 and 11.

A cylinder or cylindrical bushing 14, set 70 in the casing 8, is provided with the helical port 15 in communication with the passage 6, the similar helical port 16 and the circular ports 17 and 18 in communication with the passage 7, the similar helical port 19 in communication with the passage 12, the similar helical port 20 and the circular ports 21 and 22 in communication with the passage 13, the ports 54", 66 and 67 communicating 75 with the atmosphere, and the ports 23 and 24 in communication with the chamber 25 of the casing 8, this chamber being connected by the ports 26 and 27 with the respective passages 6 and 12 under control 80 of check valves 26' and 27'. These valves are normally held on their seats by springs 26" and 27" which are supported on bearing and guiding means 26^a secured in the 85 chamber 25 by a bolt passing through the chamber's cover plate 27^a.

A cylindrical valve 28 is movable longitudinally and revolvably in the cylinder 14 by a stem 29 which is fixed to the valve and 90 movable in the bearing 30 at the bottom of the casing 8, the stem containing a spiral groove 31 which engages a stud 32 fixed to the bearing. This valve is actuated by means of a lever 33 fulcrumed on the bearing 34 of the casing 8 and having an arm 35 containing a slot 36 through which passes a stud 37 fixed to a member 38 having a swiveled connection with the stem 31, the latter having a cylindrical part 40 provided 95 with a circular channel 41 which turns in a socket 42 of the part 38 and is held therein by a stud 43 carried by the part 38 in engagement with the part 41.

The valve 28 is provided with the helical ports 44 and 45 connected through the valve passage 46 and adapted to register simultaneously with the respective ports 15 and 16, with the helical ports 47 and 48 connected through the valve passage 49 and 100 110

adapted to register simultaneously with the respective ports 19 and 20, with the port 50 communicating with the atmosphere through the open end of the valve and adapted to 5 register with the port 17, with the ports 51' and 51 adapted to register with the respective ports 23 and 24, with the ports 52 and 52' connected with the ports 51 and 51' through the valve passage 53 and adapted 10 to register with the respective ports 18 and 22, with the port 54 adapted to register with the port 21, with the port 54' adapted to communicate with the atmosphere through the port 54'', and with the port 65 adapted to 15 communicate with the atmosphere through the port 66.

The compressor cylinder 2 contains a power or compressor piston 55 which is reciprocated by a crank shaft 56 through a 20 pitman 57, the shaft being journaled in the bearings 58 of the frame and revolved in any desired manner.

The work or ram cylinder 3 contains a fixed piston 60 and a ram 61 which is 25 adapted to reciprocate on the fixed piston in the cylinder, through the cylinder's guide 62, and to coöperate with the anvil 63 in doing work upon an article 64.

When it is desired to effect a continuous 30 reciprocation of the ram 61, the lever 33 is operated to set the valve 28 in the position shown in Fig. 6, with the passages 44, 45, 47 and 48 in registration with the respective passages 15, 16, 19 and 20. Thereupon the 35 up-stroke of the piston 55 will drive compressed air from the top of the cylinder 2 through the connected passages 4, 6, 15, 44, 46, 45, 16, 7, and 5 into the top of the cylinder 3, which drives the ram 61 down upon 40 the work; and the downstroke of the piston 55 exhausts the top of the cylinder 3 through the described passages and drives compressed air from the bottom of the cylinder 2 through the connected passages 10, 12, 19, 45 47, 49, 48, 20, 13, and 11 into the bottom of the cylinder 3, which elevates the ram 61; the different areas of the ram 61 exposed to the oppositely acting pressures, as well as the constant action of gravity, securing the 50 desired difference in the effective force involved in elevating the ram and driving it down.

When it is desired to strike a single blow and hold the ram down under pressure, as 55 in vising the work, the valve 28 is set in the position shown in Fig. 7. Now the up-stroke of the piston 55 forces air from the top of the cylinder 2, through the connected passages 4, 6, 26, 25, 24, 51, 53, 52, 18, 7, and 5, 60 into the top of the cylinder 3 (the check valve 26' being automatically opened); and the down stroke of the piston 55 forces air from the bottom of the cylinder 2, through the connected passages 10, 12, 27, 25, 24, 51, 65 53, 52, 18, 7 and 5 into the top of the cylinder

3 (the check valve 27' being automatically opened); the ram 61 being forced down by both strokes of the piston 55 and the pressure upon the work due to the ram's weight being increased by the pressure communicated to it. In this position of the valve 28, the small relief holes 17, 21, 54, 54' and 54'' communicate with the atmosphere.

When it is desired to hold the ram suspended in the elevated position, the valve 28 75 is set in the position illustrated in Fig. 8. Now the up-stroke of the piston 55 forces air from the top of the cylinder 2, through the connected passages 4, 6, 26, 25, 23, 51', 53, 52', 22, 13, and 11, into the bottom of the cylinder 80 3, and the down-stroke of the piston 55 forces air from the bottom of the cylinder 2, through the connected passages 10, 12, 27, 25, 23, 51', 53, 52', 22, 13 and 11 into the bottom of the cylinder 85 3, whereby the ram 61 receives the pressure on its under side and is held up by the force of both strokes of the piston 55. Relief is obtained through the escape of air by the registering relief passages 65 and 66, 90 the relief passages 17 and 50 registering to permit the air to escape from the top of the cylinder 3.

Having described our invention, we claim:

1. The combination with cylinders and 95 pistons therein, of a valve and passages connecting said cylinders under control of said valve, said valve being adjustable and having means for simultaneously connecting the corresponding ends of said cylinders so that 100 each stroke of one of said pistons will actuate the other of said pistons in the opposite direction, and means for simultaneously turning said valve and moving it longitudinally to change the connections between said 105 cylinders.

2. The combination with cylinders and 110 pistons therein, of a valve, passages connecting said cylinders under control of said valve, said valve being adjustable and having means for connecting both ends of one of 115 said cylinders with one end of the other of said cylinders, and non-return valves disposed in passages leading to said valve from opposite ends of one of said cylinders.

3. The combination with cylinders and 120 pistons therein, of a valve and passages connecting said cylinders under control of said valve, said valve being adjustable and having means for connecting both ends of one 125 with either end of the other of said cylinders.

4. The combination with cylinders and 130 pistons therein, of a cylindrical valve, means for turning said valve and moving it longitudinally, and passages controlled by said valve to connect the ends of one of said cylinders with the respective ends or with either end of the other of said cylinders.

5. The combination of a compressor cylin-

der, a piston movable in said cylinder, a passage communicating with each end of said cylinder, a ram cylinder, a piston movable in said ram cylinder, a passage communicating with each end of said ram cylinder, a valve casing with which said passages are connected, and means comprising a valve movable in said casing so as to connect the passages of the compressor cylinder with the 10 passages of the ram cylinder and both passages of the compressor cylinder with either passage of the ram cylinder.

6. The combination of a compressor cylinder having passages communicating with the ends thereof, a piston movable in said cylinder between said passages, a ram cylinder having passages communicating with the ends thereof, a piston movable in said ram cylinder between its said passages, a 15 valve casing connected with said passages, and means comprising valve mechanism for connecting the passages connecting with the ends of the compressor cylinder with the passages communicating with the ends of the ram cylinder and the passages communicating with the ends of the compressor cylinder with the passage communicating with either end of the ram cylinder.

7. The combination with compressor and 20 ram cylinders, of a valve case comprising a cylinder containing ports, passages connecting said ports with the ends of said compressor and ram cylinders, a cylindrical valve containing ports adapted to register with ports aforesaid, and means for turning said cylindrical valve and moving it longitudinally.

8. The combination with compressor and 25 ram cylinders, passages communicating with the respective ends of said cylinders, a valve

casing containing a cylinder provided with helical ports connected with said passages respectively, and a cylindrical valve movable in the ported cylinder and having helical ports adapted to register with the ports 30 aforesaid for connecting the respective ends of said compressor and ram cylinders.

9. The combination with compression and ram cylinders, passages communicating with the respective ends of said cylinders, a valve 35 casing containing a plurality of sets of ports respectively communicating with the ends of said cylinders, and a valve containing sets of ports adapted to register with ports of corresponding sets aforesaid.

10. The combination with cylinders having pistons therein and passages communicating with ends of said cylinders, of means for controlling said passages and comprising a casing containing helical ports communicating with the respective passages, ports communicating freely with a plurality of said passages, and ports communicating with other of said passages, check valves for controlling communication between said 45 last named ports and passages, and a valve having ports adapted to be brought into communication with ports aforesaid.

11. The combination with a cylinder and a piston therein, of means comprising a plurality of ports communicating with each end of said cylinder and a valve adapted for simultaneously opening a port communicating with each end of said cylinder and closing a port communicating with each end of 50 said cylinder.

In testimony whereof, we have hereunto set our names this 18 day of December, 1916.

E. J. FRITSCH.
RALPH W. NAZEL.
